UPRIGHT CORDLESS ELECTRIC GRASS SHEAR

James E. Edgell, Bradford Woods, Pa., assignor to
Disston, Inc., Pittsburgh, Pa.

Filed Mar. 1, 1971, Ser. No. 119,983

Term of patent 14 years

Int. Cl. D8—03

U.S. Cl. D8—8

FIG. 1 is a perspective view of an upright cordless electric grass shear embodying my new design;

FIG. 2 is a top plan view thereof;

FIG. 3 is a front elevation view of the shearing portion thereof;

FIG. 4 is a rear elevation view of the shearing portion thereof;

FIG. 5 is a side elevation view of the shearing portion thereof which is a mirror image of its laterally opposite side;

FIG. 6 is a side elevation view of the handle portion thereof which is a mirror image of its laterally opposite side;

FIG. 7 is a rear elevation view of the handle portion thereof.

I claim:

The ornamental design for an upright cordless electric grass shear, substantially as shown and described.
